H. F. LIVERMORE

MOLD FOR CONCRETE SET TUBS

Filed Oct. 2, 1924

Inventor,
Homer F. Livermore;

By, *A. B. Alpham*,
Attorney.

Patented Sept. 8, 1925.

UNITED STATES PATENT OFFICE.

HOMER F. LIVERMORE, OF BROOKLINE, MASSACHUSETTS.

MOLD FOR CONCRETE SET TUBS.

Application filed October 2, 1924. Serial No. 741,258.

To all whom it may concern:

Be it known that I, HOMER F. LIVERMORE, a citizen of the United States, and a resident of Brookline, in the county of Norfolk and 5 Commonwealth of Massachusetts, have invented certain new and useful Improvements in Molds for Concrete Set Tubs, of which the following is a full, clear, and exact specification.

10 The object of this invention is the construction of an improved mold for casting set tubs in one integral whole, and especially of double tubs, and the improvements relate to means for abolishing sharp corners within 15 the tubs; to means for supplying the tubs with an overflow; to means for rendering the casting of the tubs more perfect, and the work more expeditious; and to other details to be hereinafter disclosed.

20 In the drawings forming part of this specification, Fig. 1 is a longitudinal section of a mold embodying my improvements, the section being on an irregular line. Fig. 2 is a sectional plan view of one corner of the 25 mold, drawn nearly full size. Fig. 3 is a sectional elevation nearly full size of the front lower portion of the mold. Fig. 4 is a section of the strainer-casting.

In the manufacture of the set tubs I prefer to cast them upside down, and hence what is to form the top edges of the tubs is made close to the bottom of the mold. For such bottom, a flat metal plate 1 is removably supported upon any suitable means, 35 and upon the same are placed cores 2 the outer surfaces of which are to shape the inner-surfaces of the tubs. As shown in the left-hand portion of Fig. 1, these cores are hollow for the sake of lightness and 40 economy.

At the lower edge of each core is a slight flange 3 curving outwardly for approximately a quadrant in order to give a rounded edge to the finished tubs; each core being 45 slightly tapering to enable it to be withdrawn from the hardened concrete, and a bar 4 being provided therein by means of which to withdraw the core. It is, of course, understood that the front walls of the tubs 50 are oblique in a well known way, and that the corresponding surface of each core is to be similarly oblique, as illustrated in Fig. 3.

In addition to the cores 2, the mold comprises a front wall 5, a rear wall 6, and end walls 7. The front and back walls are formed with terminal flanges 9, and the end

walls with flanges 10; bolts 11 being used to bolt the same together. To provide the tubs with curved external corners, these walls are formed with curved flanges 12 at their lower 60 inner edges adapted to meet the flanges 3 and form therewith substantially a semi-circle, thereby giving the top edges of the finished tub a corresponding semi-circular roundness.

For the substantially vertical corners of the tubs, a fillet 13 is provided, as shown in Fig. 2, the flanged portion 9 of the side wall being recessed to permit the unbroken fillet projecting from the end wall 7 to sweep through an entire semi-circle and terminate flush with the inner surface of the side wall. Were the fillet to be divided half-and-half between an end wall and side wall, it would 70 practically be impossible to bolt the walls together without leaving a projecting seam which would have to be laboriously tooled off from the finished tubs.

As shown in Fig. 3, the cores 2 are provided with pins 14 adapted to engage holes in the foundation plate 1 for the purpose of retaining them in place thereon. After the cores have thus been placed, the side and end walls are put in position about the same and loosely bolted together. Then a clamp 15 is applied to the base flanges 16 of the end walls 7 and the latter tightly pressed against the flanges 3 of the cores; and other clamps, as 17 in Fig. 3, used to firmly seat the walls upon the plate 1. The bolts 11 may now be 80 tightened up.

To provide the tubs with an overflow, and a means for attaching the drain pipe thereto, a hollow yoke 20 has its open ends laid upon drainer-castings 21 which are placed upon the cores 2, as shown in Fig. 1; this yoke having a nipple 22 for the attachment thereto of the drain pipe, and a smaller hole opposite thereto, at 23. Through this nipple and hole is passed a rod 24 whose lower end enters a short section of rod 25 whose ends snugly fit between the two cores. The upper end of the rod 24 has a wire nail or other suitable object thrust transversely through it for the purpose of its withdrawal.

Before pouring in the concrete, the walls of the mold and rod are smeared with a suitable preparation to prevent the concrete from adhering thereto. Thus made ready, the concrete is poured in, tamped, smoothed off even with the top edges of the side and end walls, and allowed to thoroughly set.

Then the entire thing is reversed; the clamps removed; the plate 1 taken off; the cores withdrawn; the side and end walls unbolted, and the tubs set aside for perfect hardening, 5 to be followed by sand-papering and other desired finishing. Before the reversal of the mold and its contents, the rod 24 is carefully worked out, but the rod-section 25 is not pressed out from the tub-wall until 10 after the withdrawal of the cores.

In a set tub thus produced, not only are the surfaces smooth and all corners rounded, but the amount of subsequent hand work is comparatively slight; while the overflow 15 escapes through the holes left by the rods 24 and 25 down into the yoke 20 and thence to the drain.

The strainer-castings 21 are shown full size in section in Fig. 4.

20 What I claim as my invention is:

1. A mold for concrete set tubs, comprising a foundation plate, a core supported thereon, a front wall, a back wall, end walls, the latter having flanges bolted to the projecting terminal portions of the front and 25

back walls, clamps firmly holding the front and back walls down upon the foundation plate, and clamps reaching beneath the foundation plate and adapted for pressing the end walls toward each other and solidly 30 against the edges of the core.

2. A mold for concrete tubs comprising a foundation plate, a core, side walls and end walls, and means for fastening said parts tightly together, said means embracing a 35 recessed flange at each corner, a flange parallel therewith and means clamping the two flanges together, the member having the second-named flange having at the termination of its inner surface a fillet-flange extending for a quarter-circle and abutting against the end-wall of the recess of said recessed flange, whereby an unbroken curve 40 is given between two surfaces at right angles to each other.

In testimony that I claim the foregoing invention, I have hereunto set my hand this 29th day of September, 1924.

HOMER F. LIVERMORE.
